OZONE GENERATOR UNIT

William A. Pardey, Portland, Oreg.

Application October 31, 1952, Serial No. 22,073

Term of patent 14 years

(Cl. D16—2)

To all whom it may concern:

Be it known that I, William A. Pardey, a citizen of the United States, residing at Portland, in the county of Multnomah and State of Oregon, have invented a new, original, and ornamental Design for an Ozone Generator Unit, of which the following is a specification, reference being had to the accompanying drawing, forming part thereof.

The figure is a perspective view of an ozone generator unit showing my new design. The opposite end and opposite side are substantially the same as the respective end and side shown.

I claim:

The ornamental design for an ozone generator unit, as shown and described.

WILLIAM A. PARDEY.
